UNITED STATES PATENT OFFICE.

MAURICE A. PLATT, OF NEW YORK, N. Y., ASSIGNOR TO A. KIMBALL COMPANY, OF NEW YORK, N. Y., A CORPORATION OF NEW YORK.

GARMENT-MARKING TAG.

1,161,333.

Specification of Letters Patent.

Patented Nov. 23, 1915.

Application filed January 21, 1914. Serial No. 813,354.

To all whom it may concern:

Be it known that I, MAURICE A. PLATT, a subject of the King of Great Britain, and residing at New York, in the county of New York and State of New York, have invented certain new and useful Improvements in Garment-Marking Tags, of which the following is a specification, such as will enable those skilled in the art to which it appertains to make and use the same.

This invention relates to garment marking tags for use by merchants, manufacturers or dealers, and the object thereof is to provide an improved marking tag for this purpose which is particularly designed for use in marking ladies' garments, but may be used in marking any garments, and which, when once applied to a garment, cannot be detached without destroying the tag, or without leaving evidence of the fact that it has been detached and re-applied.

It frequently happens that dealers allow customers to take garments home for examination, and it also frequently happens that the said customers wear said garments one or more times and then return them, and in order to do this, they have to detach the marking tag applied thereto, and one of the objects of this invention is to provide means whereby this cannot be done, without leaving evidence of the fact.

The invention is fully disclosed in the following specification of which the accompanying drawings form a part, in which the separate parts of my improvement are designated by suitable reference characters in each of the views, and in which:

Figure 1 is a view showing one use of my improved garment marking tag;—Fig. 2 a plan view of a blank of thick or strong paper, from which the tag is made;—Fig. 3 a view showing the tag properly applied;—Fig. 4 a view similar to Fig. 1, but on an enlarged scale;—Fig. 5 a section on the line 5—5 of Fig. 4;—Fig. 6 a view of part of the device, as shown in Figs. 4 and 5, and looking in the direction of the arrow 6 of Fig. 5;—Fig. 7 a section on the line 7—7 of Fig. 5, and on an enlarged scale;—Fig. 8 a view similar to Fig. 5 but showing a modification, and showing only a part of the construction shown in Fig. 5;—Fig. 9 a back view of a blank for forming a modified form of tag;—Fig. 10 an inside view thereof and showing one step in the method of con-

necting the tag with a garment;—Fig. 11 a section on the line 11—11 of Fig. 10, and;—Fig. 12 a view similar to Fig. 11, but showing the tag completely connected with a garment.

In the drawings forming part of this specification, reference being made to Figs. 1 to 9, I have shown at *a*, in Fig. 1, a part of a lady's coat or other garment provided with lapels *a*² to one of which my improved marking tag *b* is secured. The marking tag *b* is formed from a blank *b*² of strong paper or other suitable material and oblong in form, and adapted to be folded transversely at *b*³ and *b*⁴ to form a central part *b*⁵, and two end parts *b*⁶ and *b*⁷, all of said parts being of the same dimensions, or approximately so.

In carrying my invention into effect, I place on the back of the part *b*⁷ and centrally of the free edge thereof, a thin metal tab *c* having a hole *c*² formed therein, and around said hole on one side of said tab is a projecting member or members *c*³, and the part *b*⁷ is also provided with an aperture *b*⁸ through which the member or members *c*³ pass, and said part *b*⁷ is also provided with a transverse slot *b*⁹ through which the inner end of the metal tab strip *c* is passed, folded and clenched, as shown at *c*⁴ in Fig. 5. The part *b*⁵ is provided, adjacent to the part *b*⁷, with a transverse oblong slot or opening *b*¹⁰, and adjacent to the part *b*⁶, and centrally thereof with an aperture *b*¹¹, and the part *b*⁶ is provided adjacent to the part *b*⁵ with an aperture *b*¹² which corresponds with the aperture *b*¹¹, and said part *b*⁶ is also preferably provided adjacent to its free end or edge with two apertures *b*¹³ which are adapted to register with the slot *b*¹⁰, when the blank *b*² is folded to form the tag. I also provide a pin staple *d* which is designed for use, as shown in Figs. 3, 5 and 7, and the blank *b*², folded as described, and as shown in Fig. 5, together with the sheet metal tab *c*, having the hole *c*² and projecting member or members *c*³, and the wire staple *d* constitute my complete marking tag.

In the use of this device, as shown in the drawing, one of the lapels *a*² of the garment is inserted between the parts *b*⁶ and *b*⁵ of the tag, as shown in Fig. 5, and the side arms of the staple *d* are passed through the apertures *b*¹³ in the part *b*⁶ of the tag, through the lapel *a*² and through the slot *b*¹⁰ in the

part b^5 of the tag, and clenched, as shown at d^2 in Fig. 7. The member or members c^3 of the sheet metal tab c are then passed through the apertures b^{11} and b^{12} in the parts b^5 and b^6 , said member or members having previously been passed through the aperture b^8 in the part b^7 , and said member or members are clenched, as shown in Figs. 5 and 6. Any desired printed, written, or other matter may be placed on the tag b , and when applied in the manner described, it will be evident that said tag cannot be detached from the garment and re-applied, without leaving evidence of the act.

The construction shown in Fig. 8 is the same as that shown in Figs. 1 to 7 inclusive, except that for the sheet metal tab c I provide a longer tab c^5 which is placed on the part b^6 of the tag, and one end portion of which is folded around the other parts b^5 and b^7 and passed through the part b^7 and clenched, as shown at c^6 , while the end portion which rests on the part b^6 of the tag is provided with a hole c^8 and a projecting member or members c^9 which are passed through the parts b^6 , b^5 and b^7 , and clenched, as shown at c^9 in said Fig. 8.

It will be understood that my invention is not limited to the formation in the blank b^2 , or the separate parts thereof, of the apertures b^8 , b^{11} , b^{12} and b^{13} , nor the slot b^{10} , as the staple d may be passed through the separate parts of the tag, as shown in Figs. 3, 5 and 7, without the slot b^{10} and apertures b^{13} , and the member or members c^3 of the tab c may be passed through the separate parts of the tag shown in Fig. 2, and as indicated in Figs. 3, 5 and 7, without the apertures b^8 , b^{11} and b^{12} .

In Figs. 9 to 12 inclusive, I have shown another modified form of marking tag and modified method of connecting the same with a garment, and this tag is formed from a blank e of stiff paper folded centrally at e^2 to form two similar parts e^3 and e^4 . The part e^3 , in the construction shown, is provided on the outer side and at the free edge thereof with a sheet metal tab f , similar to the tab c , shown in Figs. 1 to 7, inclusive, and the inner end of which is passed through the part e^3 of the tag at f^2 and clenched on the outer side of the part e^3 , as shown at f^3 , the part e^3 of the tag is also preferably provided under the tab f with the aperture e^5 , and the part e^4 is preferably provided adjacent to its free edge with a corresponding aperture e^6 . I have also shown at g a part of a garment, and in connecting the tag, shown in Figs. 9 and 12, with the garment, a part of said garment is placed on the back e^4 of the tag, or said part of the tag is laid on said part of the garment, and a safety pin h is passed through a part of the garment and through the part e^4 of the tag, after which the part e^3 of the tag is folded over

the part e^4 and over the safety pin, or that part thereof which is passed through the garment, and the part e^4 of the tag and as shown in Fig. 12, and the tab f is provided with a punch hole i and on one side thereof with a projecting member or members f^3 which are passed through the hole or aperture e^6 and clenched, as shown in Fig. 12.

As hereinbefore stated, the tag or blank e from which the said tag is formed is composed of stiff paper, and when the pin h has been passed through the part g of a garment and through the part e^4 of the tag and secured in the ordinary manner, and as shown in Fig. 10, and the part e^3 of the tag folded over and secured to the part e^4 , as shown in Fig. 12, it will be impossible to detach the tag and re-apply it to the garment, without showing evidence of the act, and in fact, this detachment of the tag cannot be accomplished without practically destroying it. This form of my invention is not limited to a safety pin h , or the use thereof, and an ordinary staple pin, similar to that shown in Figs. 3, 5 and 7 may be employed if desired, and if the tag, or the separate parts thereof are made small enough, it will be apparent, that after the tag has been secured to the garment, or a part thereof, as shown and described, even the form of fastening or locking pin shown in Figs. 3, 5 and 7 cannot be removed and re-applied.

From the foregoing description, it will be seen that the sheet metal tab c , shown in Fig. 1, or c^5 and c^{10} , shown in Figs. 8 and 9, or the sheet metal tab f , shown in Figs. 10 to 13 inclusive, constitute the chief feature of this invention, and said tab may be secured to the tag, or a part thereof, in its sheet form only, and may be punched and provided with teeth, which are passed through the separate parts of the tag and clenched in the operation of applying or securing the tag to a garment, or the said tab may be secured to the tag, or a part thereof, and punched and provided with teeth by the manufacturer of the tag, and other changes in and modifications of the construction herein described may be made, within the scope of the appended claim, without departing from the spirit of my invention, or sacrificing its advantages; and although I have shown and described my improved marking tag as intended for use in marking garments, it will be apparent that said tag may be used for various other purposes, and for marking other articles or parts thereof. It must also be understood that my invention is not limited to the idea of securing the tab to the back of one part of the tag, when said tag is manufactured and placed on the market, and especially is this true of the folded form of tab shown in Figs. 8 and 9, and tabs of this form may be made separately and independently supplied

by the manufacturer, and may be applied to the tag in the operation of securing said tag to a garment, and in supplying tabs in this manner, one part, or end portion thereof, will be punched to form an eyelet or aperture and a projecting member or teeth on one side thereof, which member or teeth in the operation of securing the tag may be passed through the separate parts of the tag, and through the other part of the tab and clenched, as will be readily understood.

Having fully described my invention, what I claim as new and desire to secure by Letters Patent is:—

15 A garment tag composed of an oblong sheet of flexible material adapted to be folded to form a plurality of similar parts, one of said parts being adapted to be secured to a garment and being provided at

one of its ends with an aperture, and a sheet 20 metal tab provided with a tongue which passes through the free end of another part for permanent engagement therewith, said tab being also provided with a cylindrical member which also passes through said last 25 named part and is adapted to be passed through said aperture and clenched when the tag is applied to a garment to secure the free ends of the said parts together.

In testimony that I claim the foregoing as 30 my invention I have signed my name in presence of the subscribing witnesses this 19th day of January 1914.

MAURICE A. PLATT.
